UNITED STATES PATENT OFFICE

HARRY W. RUPPLE, OF CLEVELAND, OHIO, ASSIGNOR TO THE CLEVELAND AUTOMATIC MACHINE CO.

METAL-WORKING MACHINE

Application filed August 29, 1925. Serial No. 52,242.

This invention relates to metal working machines and refers more particularly to improvements in the threading mechanism thereof, the purpose being to provide a machine of the class adapted to thread the ends of bolt blanks which will produce a more uniform character of threaded articles. In the present types of screw threading apparatus, it is customary to rotate either the threading die or the work, or both, and to positively move the die during the initial part of its travel until engaged upon the work, thereafter relying on such engagement to further advance the die. Other forms consist of means such as a cam adapted to engage a projection on the die slide to move the same during its travel. In these present known constructions, it is found that after being in use for a short time, the wear on the parts results in an unevenly threaded product and therefore great difficulty has been encountered to produce a precision type of bolt.

This invention has for its general object to provide operating mechanism directly connected to the threading slide which is adapted to positively move the threading die at its proper pitch speed irrespective of the wear on the threading elements of such die. The present mechanism is especially designed to reduce as much as possible the wear in the operative elements of the die slide advancing mechanism. A further object of the invention is to provide driving mechanism for rotating the work holder and co-operative means actuated from such driving mechanism for operating the die slide feed mechanism.

To the accomplishment of the foregoing and related ends, said invention, then, consists of the means hereinafter fully described and particularly pointed out in the claims.

The annexed drawings and the following description set forth in detail certain mechanism embodying the invention such disclosed means constituting, however, but one of various mechanical forms in which the principle of the invention may be used.

In said annexed drawings:—

Fig. 1 is a plan view of a single spindle

metal working machine of which only the work holder spindle, the cooperating tool and their driving mechanism are shown.

Fig. 2 is a front side elevation thereof.

Fig. 3 is an enlarged view partially in section of the threading die and its feeding mechanism.

Fig. 4 is a cross-sectional view taken on line 4—4 of Fig. 3, looking in the direction of the arrows.

Fig. 5 is a detailed sectional view of the lead screw and the nut carrying head; and

Fig. 6 is a detailed view illustrating the mechanism for automatically opening the lead screw nuts.

The present embodiment of the invention illustrated in the drawings describes an automatic metal working machine of the single spindle class, having a work carrying mechanism mounted at one end of the bed plate and an aligned tool carrying mechanism mounted at the other end thereof. It is to be understood, however, that the invention contemplates the adaptation of the present improvements in the threading die feeding mechanism on machines of the multiple spindle class, or other types having a threading die which is to be reciprocated with respect to the work.

The bed plate of the machine is indicated generally at 10 and the work carrying spindle 11, which latter member is suitably journaled in projections 12 on the top of the bed plate and has a chuck 13 on its front end. Also journaled in projections 12 is a driving shaft 14 carrying a pulley 15 which may be connected to any suitable source of power. Spur gears 16 and 17 are mounted on shaft 14 at either side of said pulley. The gear 16 is arranged to drive the spindle 11 through a gear 18 mounted thereon, while the gear 17 meshes with a gear 19 mounted on a longitudinally extended shaft 20. The shaft 20 is carried by vertical brackets 21 provided on the bed plate 10 and serves to actuate the threading die feeding mechanism, as will appear more fully hereinafter.

The work carrier herein shown consists of the hollow spindle type having the usual means (not shown) located at its far end for

feeding stock at proper intervals and for automatically actuating the gripping jaws of the chuck 13. As seen in Fig. 2, the work is projected from the front end of such chuck 5 in a position to be operated upon by the threading mechanism, and a cut-off tool may be provided on a cross slide member to sever the proper length from the stock bar after having been operated upon by the threading 10 mechanism.

The threading die is indicated in the drawing at 25 and is carried on the front end of a longitudinally extended slide 26 journaled in projections 27 of a bracket 28 mounted on 15 the top of the bed plate 10. The die 25 may be of the self opening and closing type having a co-operating stop 29 adjustably positioned in advance of the same for opening and a yoke member 30 adapted to engage the 20 die in its rearward movement to close the same preparatory to the succeeding threading operation. The rearwardly projecting portion 31 of the slide 26 is of tubular cross section as shown in Fig. 3 and carries therein 25 means as a lead screw 32 which is adapted to advance the threading die at exactly the proper pitch speed. On the slide 26 between the brackets 27 is fixed an arm 33 which projects downwardly and slidably engages a 30 stub shaft 34 mounted by the brackets 27 parallel with the slide 26. This arrangement permits reciprocation of the slide 26 while preventing rotation thereof.

Shaft 20 hereinbefore referred to extends 35 to the far end of bracket 28, being supported thereon by a vertical projection 36 and having spur gear 37 secured to its end. A second gear 38 carried on the lead screw shaft 39 meshes with the gear 37 and establishes 40 driving relation between the lead screw and the pulley 15. The shaft 39 and lead screw 32 are projected interiorally of the tube 31 and have a bearing at the forward end in a bushing 40 mounted against a shoulder 41 on the 45 inside of such tube, it being apparent that as the threading die is advanced, the tube 31 moves longitudinally with respect to the shaft 39. Therefore, the forward end of such latter shaft is projected a suitable distance 50 beyond the bushing 40 to insure support thereof at the time when the threading die is in its advanced position. The rear end of the shaft 39 is journaled in a bushing 43 mounted in the projection 36 and is provided 55 with a split collar 44 which serves to lock the same from relative longitudinal movement. A thrust bearing 45 is positioned between the collar 44 and the face of the bracket 36. 60 The construction described immediately above provides for the changing of the lead screw which is required depending upon the pitch of the threading die. The collar 44 is first removed from the shaft and then the 65 entire lead screw and shaft 39 may be pulled

rearwardly through the bore in the bushing 43.

The lead screw proper, indicated at 32, comprises a tube having its exterior threaded and its interior adapted to fit the shaft 39. When assembled the rear end of lead screw 32 is engaged with a shoulder 46 on the shaft 39 and the forward end thereof is engaged by a lock nut 47 threaded on a portion 48 of the shaft 39. By this construction the shaft 39 75 may be used with several different lead screws. To insure positive driving relation between the shaft 39 and the lead screw, the rear end of which screw may be provided with a slotted portion 50 to engage with a transverse pin 51 mounted in the shaft 39.

Carried on the rear end of the tubular threading die slide 31 is an annular member 52 in which are mounted a pair of half nuts 53. The member 52 is fixedly mounted on the end of slide 31 in any desired manner, the construction being here shown in detail in Fig. 5 as by screw threading the same thereon and locking the parts together by a set screw 54. The half nuts 53 are located diametrically of the member 52 to engage opposite sides of the lead screw 32 when moved toward each other, it being obvious therefore that when so engaged the die slide will be advanced upon rotation of the lead screw. It 95 will also be apparent that on account of the arm 33 the member 52 will be held from rotation. Projecting longitudinally from one side of the nuts 53 are pins 55 which are received in eccentric slots 56 provided in an oscillatory shell 57. This shell 57 is of cup shape having its annular wall fitted to the exterior of the member 52, and its base portion provided with the slots 56 and an opening 59 in which is received the lead screw. 105 Mounted at the top of shell 57 is a cam projection 60 adapted to be engaged by a cam 61 carried by an operating arm 62. The arm 62 is fixed to a rotatable sleeve 63 supported between the brackets 27 and 36 by bearings 110 64 on the shaft 20. As seen in Fig. 4, the cam 61 is pivotally mounted on the arm 62 about a pin 65 and engaging against one surface thereof is a spring pressed plunger 66. In the construction of a rotating screw and 115 separable half nuts, it sometimes happens that as the half nuts 53 are moved together to engage the threads of the lead screw, the relative threads on the nuts fall on the raised lands of the threads of the lead screw, and if a positive cam action were provided, injury might result to such mechanism in those cases. By the construction described above, it will appear that should such improper engagement occur, the spring 120 pressed plunger will permit a certain yielding of the cam 61 until the lead screw has rotated a sufficient distance to permit engagement of the half nuts.

Mounted parallel to the work holding and 125

threading die spindles between brackets 21 is a cam shaft 70 carrying thereon a cam drum 71 disposed adjacent the threading die spindle. This cam shaft may be driven by suitable gearing (not shown) from the pulley shaft 14. Mounted on one end of the cam drum 71 is a cam plate 72 adapted to engage a cam roller 73 carried at the outer end 74 of an arm 75, which latter member is mounted on the sleeve 63. The cam drum is also provided with a peripheral cam plate 76 adapted to engage at intervals a cam roller 77 mounted on a rearwardly projecting portion 78 of the arm 33. In operation the cam 72 serves to engage the half nuts 53 with the lead screw while the cam 76 is employed to return the threading die slide to its initial starting position, the pitch of cam 76 being acute to rapidly return such slide.

20 The invention also contemplates the provision of means automatically operated to cause the separation of the half nuts from the lead screw just prior to the engagement of the roll 77 with the cam 76. As seen in Figs. 4 and 6, these means comprise a spring pressed plunger member 80 mounted in the shell 57 and having an outwardly projecting pin 81 and a collar 82. The inner end of the plunger is adapted to engage against the shoulder 83 of a recessed portion 84 in the member 52 to hold the shell together with the half nuts 53 in locked or engaged relationship with the lead screw. Also mounted on the shell 57 is a pivoted arm 85 having one end bifurcated at 86 to engage around the pin 81 under collar 82, and the other end 87 projected forwardly beyond the edge of the member 52. Carried in the adjacent bracket 27 is an adjustable cam pin 88 having its end 40 inclined at 89 to engage the end 87 of arm 85 as the die slide is advanced. This pin 88 is adjusted to withdraw the plunger 80 from the recess in the member 52 at the time when the threading of the article is completed.

45 Means for automatically rotating the shell 57 to withdraw the half nuts from engagement with the lead screw consist of compression springs 90 mounted in recesses 91 in the member 52 and engaging latterly projecting pins 50 92 fixed in the shell 57.

To reduce the strain and to strengthen the lead screw mechanism, the present invention proposes to construct such lead screw with threads having one-half the pitch of the threads desired to be formed on the article. The same obviously provides a more rigid and more uniform feed of the die slide. Consequently, the speed of the lead screw must be twice that of the work, which may 60 be easily accomplished by providing the proper gear ratio between the gears 17 and 19.

Other modes of applying the principle of my invention may be employed instead of the one explained, change being made as regards 65 the mechanism herein disclosed, provided the

means stated by any of the following claims or the equivalent of such stated means be employed.

I therefore particularly point out and distinctly claim as my invention:

1. In a threading machine of the character described, the combination of a work holder, a threading die aligned therewith, a reciprocable slide carrying said die, driving means for rotating said work holder, a rotatable lead screw mounted coaxially of said slide, said screw being adapted to actuate said die slide in its advancing movement, and said screw being held from longitudinal movement with said slide, and means for actuating said lead screw from said driving means.

2. In a machine of the character described, the combination of a rotatable work holder, driving means therefor, a threading die mounted at one end of a reciprocable slide, a revoluble cam, feeding means mounted coaxially of said slide adapted to advance the same at the proper pitch speed of the die threading elements, means actuated from said cam for effecting the operation of said feeding means, and means operated from said cam for returning said slide.

3. In a threading machine of the character described, the combination of a rotatable work holder, driving means therefor, a threading die mounted at one end of a reciprocable slide, rotatable feeding means mounted coaxially of said slide, means for engaging said feeding means with said slide, and intermittently operated means for actuating said engaging means, said feeding means being held from longitudinal movement with said slide.

4. In a threading machine of the character described, the combination of a rotatable work holder, driving means therefor, a threading die mounted at one end of a reciprocable slide, a rotatable lead screw mounted in the other end of said slide, and intermittently operated means adapted to engage said screw with said slide to positively move the latter during its threading movement, said screw being held from longitudinal movement with said slide.

5. In a threading machine of the character described, the combination of a rotatable work holder, driving means therefor, a threading die mounted at one end of a reciprocable slide, a lead screw mounted coaxially of said slide, means for rotating said screw from said driving means, and means operated from the driving means for intermittently engaging said screw with said slide.

6. In a threading machine of the character described, the combination of a rotatable work holder, driving means therefor, a threading die mounted at one end of a reciprocable slide, a lead screw mounted coaxially of said slide, means for rotating said screw from said driving means, and means operated from the driving means for intermittently engaging said screw with said slide.

ially of said slide, said screw being held from longitudinal movement, means for engaging said screw with said slide at the limit of its retracted movement, and means for disengaging said screw from the slide at the limit of its forward movement.

7. In a machine of the character described, the combination of a rotatable work holder, driving means therefor, a threading die mounted at one end of a reciprocable slide, a rotatable lead screw mounted coaxially of said slide, means for engaging said screw with said slide at the limit of its retracted movement, means for disengaging said screw from the slide at the limit of its forward movement, and means for returning said slide to starting position independently of said lead screw.

8. In a threading machine of the character described, the combination of a non-rotatable reciprocable slide, a threading die mounted on one end thereof, a rotatable lead screw coaxially mounted in the other end thereof, and separable half-nuts carried by said slide adapted to engage with said lead screw.

9. In a threading machine of the character described, the combination of a non-rotatable reciprocable slide, a threading die mounted on one end thereof, a rotatable lead screw coaxially mounted in the other end thereof, said screw being held from reciprocation with said slide, separable half-nuts carried by said slide, and means for engaging said nuts with said lead screw to actuate said slide in its threading movement.

10. In a threading machine of the character described, the combination of a non-rotatable reciprocable slide, a threading die mounted on one end thereof, a rotatable lead screw coaxially mounted in the other end thereof, separable half-nuts carried by said slide, automatically operated means adapted to engage said nuts with said screw at the starting position of the threading die, and means for disengaging said nuts at the completion of the threading movement.

11. In a machine of the character described, the combination of a non-rotatable reciprocable slide, a threading die mounted on one end thereof, a rotatable lead screw mounted in the other end thereof, an enlarged annular member mounted on said other end of the slide, transversely movable half-nuts mounted in said member, a rotatable shell mounted on said member, and means actuated by the rotation of said shell for engaging said nuts with said lead screw.

12. In a machine of the character described, the combination of a non-rotatable reciprocable tubular slide, a rotatable lead screw mounted in one end thereof, an enlarged annular member mounted on said end, half-nuts carried by said member, a rotatable shell mounted on said member hav-

ing eccentric slots therein, pins on said half-nuts projecting into said slots, and means for rotating said shell to engage said nuts with said lead screw.

13. In a machine of the character described, the combination of a reciprocable tubular slide, a rotatable lead screw mounted in one end thereof, an enlarged annular member mounted on said end, half-nuts carried by said member, a rotatable shell mounted on said member having eccentric slots therein, pins on said half-nuts projecting into said slots, means for rotating said shell to engage said nuts with said lead screw, and means for locking said nuts in engaged position.

14. In a machine of the character described, the combination of a reciprocable tubular slide, a rotatable lead screw mounted in one end thereof, an enlarged annular member mounted on said end, half-nuts carried by said member, a rotatable shell mounted on said member having eccentric slots therein, pins on said half-nuts projecting into said slots, means for rotating said shell to engage said nuts with said lead screw, and means carried by said shell adapted to cooperate with a recess in said member to retain said nuts in engaged position.

15. In a machine of the character described, the combination of a reciprocable tubular slide, a rotatable lead screw mounted in one end thereof, an enlarged annular member mounted on said end, half-nuts carried by said member, a rotatable shell mounted on said member having eccentric slots therein, pins on said half-nuts projecting into said slots, means for rotating said shell to engage said nuts with said lead screw, means for locking said nuts in engaged position, and spring pressed means adapted to rotate said shell to disengage said nuts upon release of said locking means.

16. In a machine of the character described, the combination of a reciprocable tubular slide, a rotatable lead screw mounted in one end thereof, an enlarged annular member mounted on said end, half-nuts carried by said member, a rotatable shell mounted on said member having eccentric slots therein, pins on said half-nuts projecting into said slots, a cam projection on said shell, and a rotatable cam adapted to engage said projection to rotate said shell.

17. In a machine of the character described, the combination of a reciprocable tubular slide, a rotatable lead screw mounted in one end thereof, an enlarged annular member mounted on said end, half-nuts carried by said member, a rotatable shell mounted on said member having eccentric slots therein, pins on said half-nuts projecting into said slots, a cam projection on said shell, a rotatable arm, and a yielding cam carried by said

arm adapted to engage said cam projection to rotate said shell.

18. In a threading machine of the character described, the combination of a rotatable work holder, an aligned reciprocating slide, a threading die mounted on the front end of said spindle, a rotatable lead screw mounted coaxially in the other end of said slide, means for rotating said screw, means for engaging said screw with said slide to positively move the latter during its threading movement, means for disengaging said screw from the slide upon the completion of said threading movement and means for holding said screw from longitudinal movement.

15 19. In a machine of the character described, the combination of a non-rotatable reciprocating hollow slide, a rotatable lead screw mounted coaxially within said slide, a bearing mounted within said slide for slidably supporting the inner end of said screw, and means mounted externally of said slide for supporting the outer end of the lead screw.

25 Signed by me this 18th day of August, 1925.

HARRY W. RUPPLE.
